SAUCEPAN OR THE LIKE

Patricia A. Luzier and Gregory Mirow, Corning, N.Y., assignors to Corning Glass Works, Corning, N.Y.

Filed Aug. 20, 1971, Ser. No. 173,737

Term of patent 14 years

Int. Cl. D7—02

U.S. Cl. D7—97

Fig. 1

Fig. 3

FIG. 1 is a top plan view of a saucepan or the like embodying our new design.

FIG. 2 is a side elevational view, the side opposite being identical thereto.

FIG. 3 is an end elevational view, the end opposite being identical thereto.

The characteristic feature of the design resides in the particular ornamentation applied to the outer wall, as shown.

We claim:

The ornamental design for a saucepan or the like, as shown and described.
